UNITED STATES PATENT OFFICE

99,179

DESIGN FOR A CANDLESTICK BASE OR SIMILAR ARTICLE

Karl Auth, Stratford, Conn.

Application February 18, 1936, Serial No. 61,226

Term of patent 3½ years

To all whom it may concern:

Be it known that I, Karl Auth, a citizen of the United States, residing at Stratford, county of Fairfield, State of Connecticut, have invented a new, original, and ornamental Design for a Candlestick Base or Similar Article, of which the following is a specification, reference being had to the accompanying drawing, forming part thereof.

Fig. 1 is a plan view of a candlestick base or similar article, showing my new design. The ornamentation is not completely shown, it being understood that the completion thereof would involve a mere repetition of the part shown.

Fig. 2 is a side elevation thereof.

I claim:

The ornamental design for a candlestick base or similar article, substantially as shown and described.

KARL AUTH.
